STEAM TURBINE WORKING WITH WET STEAM

Ulrich Meiningshaus, Muelheim-Ruhr, Germany

Application March 7, 1935, Serial No. 9,725
In Germany April 24, 1934

8 Claims. (Cl. 253—16.5)

My invention relates to steam turbines which include a stage working with wet steam and more particularly to the low pressure blading of such turbines, especially of turbines for large quantities of steam of high initial pressure or great heat drop. The object of my invention is to diminish or eliminate the erosion of the blades impinged by the wet steam.

The water drops contained in wet steam are not capable of following the sudden acceleration imparted to the steam itself in the blade channels. They do not, therefore, attain the same high velocity as the steam, i. e. their velocity of flow c' is lower than the velocity of flow c of the steam. If the ratio of the circumferential speed u to the steam velocity c is chosen close to unity—as has to be done, for instance, at the blade tips of axial flow steam turbines with high circumferential speeds and long blades—the ratio u/c' (circumferential speed to the velocity of the water drops) exceeds unity and the water drops will hit the rear side of the blades with heavy impact causing erosion. There is no way of avoiding this drawback effectively with long axial flow blades of high circumferential velocity because the ratio u/c cannot be diminished without great sacrifice of efficiency in view of the low ratio u/c already prevailing at the blade roots where the circumferential speed is often only 60% of the circumferential speed at the blade tips.

With the object of diminishing or eliminating erosion of the blades or of allowing for a higher degree of humidity of the steam with the same rate of erosion I propose to arrange the low pressure blades in the region of humidity in radially traversed blade rings with inlet edges running in an axial direction, the circumferential speed of each of such blade rings relatively to the circumferential speed of the next following blade ring being less than 85% of the steam velocity in said blade rings.

The invention is illustrated by way of example on the accompanying drawings wherein

Fig. 1 shows a section through a steam turbine with a single rotating high pressure part, double rotating medium pressure part, and a single rotating single flow low pressure part, and

Fig. 2 shows a section through an alternative design of the medium and low pressure part wherein the single rotating low pressure part is constructed according to the double flow principle.

Fig. 3 shows a fragmentary section through the wet steam blading.

In Fig. 1 the numerals 1 and 2 represent coun-

terrunning electric generators, the generator 1 rotating at 3000 R. P. M. and the generator 2 at 1500 R. P. M. The shaft 3 of the generator 1 carries on both stub ends discs with radially traversed blading, while the shaft 4 of the generator 2 carries such a disc only on the stub end shown in Fig. 1, the other stub end of the shaft 4 being used to drive the exciter, the governor, and the oil pumps (not shown) for both generators which are electrically coupled with each other. The shafts 3 and 4 are supported in the bearings 5. The steam enters at 6 into the high pressure housing 7 and flows successively through the radially traversed blade rows of the two discs 8 and 9 which rotate at 3000 R. P. M. and cooperate with the stationary discs 10 and 11. The rotational speed of 3000 R. P. M. and the small diameters are well adapted to expand the small volume of the high pressure steam with high efficiency at low velocities and without labyrinth losses. The partly expanded steam is led to the counter running medium pressure part of the turbine through the pipe 12. As the steam pressure is already diminished at this point and the steam volume accordingly increased the labyrinth losses due to the counter running principle are not of great influence and the high relative speed of rotation of the counterrunning rotors provides for efficient expansion of a great part of the pressure head within small space. The counterrunning is effected by rotating the disc 13 at 3000 R. P. M. in the one direction and rotating the disc 14 at 1500 R. P. M. in the other direction. The relative speed of rotation, therefore, amounts to 4500 R. P. M. The double rotating principle requires 3 labyrinth packings 15, 16, and 17 the labyrinth 17 providing at the same time for equalizing the thrust of disc 14. It is assumed that the thrust of disc 18 which is exposed to low pressure steam only is low so that no special arrangement besides a conventional thrust bearing (not shown) for equalizing said thrust is required. The thrust of the disc 13 is balanced by the sum of the thrusts of the discs 8 and 9.

According to my invention, the inlet edges of the blades 18' and 19' fixed to the discs 18 and 19 run in axial direction and the relative circumferential speed of said blades relative to the circumferential speed of the next following blade ring is diminished below a value corresponding to 85% of the steam velocity in said blades. In the example shown in Fig. 1 the diminution of the circumferential speed of the blades fixed to the discs 18 and 19 relatively to each other is accomplished by arranging part of the blades on the stationary

disc 19 while the discs carrying the blades ahead of said blades run both in opposite direction. In this way, the circumferential velocity of the blades fixed on discs 18 and 19 relatively to each other along the whole length of the blades is considerably smaller than the steam velocity in said blades, at least smaller than 85% of said steam velocity. Without any abrupt change in the steam velocity occurring, i. e. without any abrupt change of the blade area, the steam velocity c suddenly becomes far greater than the circumferential speed at the point of leaving the blading of the discs 13 and 14 and entering the blading of the discs 18 and 19. The water drops developing in the blading of the discs 18 and 19 are accelerated up to a velocity about equal to the circumferential speed without difficulty and any impact on the rear side of the blades is avoided. As the rotational speed decreases from the relative amount of 4500 R. P. M. to 1500 R. P. M. at this point I find it of advantage to diminish the steam velocity simultaneously to a certain amount. This gives at the same time sufficient freedom to adapt the steam velocity to the circumferential speed which progressively increases with the outward flow of the steam and to keep the ratio u/c below the limit given above. A less abrupt change in the relative circumferential speed would be obtained if both generators 1 and 2 were to rotate at 1500 R. P. M., but the work done in the high pressure and the medium pressure parts would be lower. The arrangement chosen offers special advantages as regards dividing the work between the different parts of the turbine.

In Fig. 2, the corresponding parts are designated by the same reference numbers. As the turbine shown in Fig. 2 is designed for very large steam volumes the blading of the discs 13 and 14 is divided into two parallel blade channels to avoid an excessive length of the blades. The blading of the discs 18 and 19 is divided in the same way. To provide for a diminution of the steam velocity at the entrance of such blading and to render possible a further increase in the blade area in the later stages, about half of the steam is taken off before the steam enters the blading of the discs 18 and 19 and is led through pipe 20 to the blading on discs 18a and 19a at the other end of the generator 2 which blading is similar to the blading of the discs 18 and 19. The blading of the discs 18a and 19a is traversed in parallel flow to the blading of the discs 18 and 19 and as each of the bladings has two passages, four parallel passages are offered to the steam, allowing for ample flow area even for great steam volumes. The thrusts of the discs 18 and 18a are opposed and balance each other. The high pressure part at the left stub end of the shaft 3 is not shown in Fig. 2, but may be assumed to be like the arrangement shown in Fig. 1.

The reduced relative speed of the blading with reference to the wet steam can be accomplished in various ways. Primarily, the construction is such that the totality of the blade channels or constrictions 21 (Fig. 3) are made smaller than heretofore for the same conditions of operation. In this way higher steam velocities are obtained and correspondingly higher pressure drops per stage, the number of blade rings required for the expansion of the wet steam being, of course, reduced for a given circumferential velocity. Substantially the same result may, however, be obtained by keeping the number of blade rings fixed (that is, the same as in prior turbines operating

under the same conditions), and reducing the diameter of the rings and hence their circumferential velocity, or the rotations per minute can be reduced. Whichever of these measures is resorted to, care should be taken that the velocity of the wet steam in the blading should be more than about 18% greater than the relative circumferential speed of the blading, regardless of whether one set of blade rings is fixed or runs oppositely to the other set of blade rings.

By using blades with inlet edges running in axial direction as shown in Figs. 1 and 2, the advantage is obtained that the value of the circumferential speed u is constant along the total length of the inlet edges. It is, therefore, possible to choose throughout the whole length of the blades a circumferential speed u which allows the steam velocity c along the whole length of the blades to be kept just so much higher than such circumferential speed as is sufficient to accelerate the water drops enough to prevent erosion and yet obtain a fair efficiency for the flow of the steam. Doing away with the braking effect of the water drops will more than outweigh the small sacrifice in the efficiency of the steam flow. With axial flow blades the circumferential speed at the blade tips is up to almost 70% higher than at the blade roots. If the ratio u/c is made close to unity at the blade tips to allow at least for efficient flow of the steam (no regard being paid to erosion or the braking effect caused by the water drops) the ratio u/c at the blade roots may drop to the value 0.6 which value diminishes already the efficiency of the steam flow. No possibility exists, therefore, in axial flow turbines with long blades in relation to the mean diameter diminishing the ratio u/c at the blade tips to less than 0.85 because the efficiency of the steam flow would be too much impaired at the other parts at the blades, especially at the roots of the blades. Furthermore, the great heat drop in the last blade rows which usually run with high circumferential speeds (up to 400 m/sec.) causes a very rapid expansion of the steam and requires, therefore, an abrupt increase in flow area from blade row to blade row. The larger the blade length, the larger the increment of the length for the same ratio of expansion, the required increment exceeding mostly the value permissible in view of efficient steam flow. The increment is, therefore, often restricted and such restriction causes the steam velocity to decrease in the stages preceding the last stage if the steam velocity in the last stage is not to exceed a maximum value. As the circumferential speeds of adjacent axial flow stages are substantially equal, the value of u/c must necessarily drop in the preceding stages thus promoting erosion and braking effect in such stages. It is a well known fact that the erosion is often found to be worst at the blade tips or close to the blade tips of the stages preceding the last one. Radial flow blading adapts the circumferential speed to the decrease in the steam velocity in the preceding stages and allows—at least if rotating blades co-operate with stationary blades—for ample possibility of increasing the steam velocity in the last stage, whereas axial flow blading or counter-running radial flow blading, especially when designed for great steam volumes, work with such enormous relative circumferential speed (up to 400 meter/sec.) that the steam velocity c cannot be much increased above such value with standard blade shapes, but only with Laval nozzles which, however, are not suitable for use with 70 standard blade shapes, but only with Laval nozzles which, however, are not suitable for use with 75.

low pressure blading. With my proposal to use stationary blades with entrance edges running in an axial direction also in that part of a steam turbine which is traversed by wet steam I make it possible for the first time to avoid or diminish erosion with certainty under the severest conditions.

The increased velocity of the moist steam with reference to the relative circumferential velocity of the blades 18, 19 is obtained, as will be readily understood, by suitable design of the blade rings whereby the necessary constrictions are provided in the path of the steam, the blading being designed in known manner in accordance with the volume of steam passing per unit of time which in turn depends upon the degree of expansion, the pressure, the temperature and the weight of steam per unit of time.

The present invention, as will be clear from the above, contemplates directing substantially all of the steam which has reached the wet condition, following its partial expansion, into a radial flow turbine having the relative speed described hereinbefore. In plants employing intermediate superheating wherein wet steam is converted to the dry condition, the steam may leave the plant in the dry state. In such a plant the present invention may be taken advantage of in the stage utilizing the wet steam immediately in advance of the superheating. It will thus be apparent that the present invention is not limited in its application to the very last stage of the plant, but may be incorporated in a turbine stage employing wet steam either before the superheating or after the superheating.

I claim:

1. A steam turbine plant wherein steam is expanded from a substantially dry state to the wet state containing droplets of condensed moisture, comprising a casing, a shaft journaled in the casing, rotating blade-carrying discs mounted on said shaft, an inlet for dry steam under pressure leading to said discs, stationary discs fixed to said casing, radially traversed rotating blades with entrance edges running in axial direction disposed to be impinged by wet steam and supported by the rotating discs, and stationary blades alternating with said rotating blades and supported within the casing, said rotating blades being grouped into blade rings providing channels in the path for the steam, said channels being so dimensioned and the number, diameters and normal speed of revolutions of the rotating rings being so determined as to compel the steam to attain in the blades a velocity relative to the blades which is more than about 18% above the circumferential speed of rotating blades relative to the stationary blades.

2. A steam turbine plant wherein steam is expanded from a substantially dry state to the wet state containing droplets of condensed moisture, comprising a casing, two shafts journaled in the casing, rotating blade-carrying discs mounted for rotation in opposite directions on said shafts, an inlet for dry steam under pressure leading to said discs, the blading on certain of said discs being disposed to be traversed by the steam while it is in the substantially dry state, radially traversed blades with entrance edges running in axial direction disposed to be traversed by the steam after it has been expanded to the wet state in the first-mentioned blades and supported by certain of said discs, and radially traversed blades alternating and cooperating with the aforementioned radially traversed blades, said radially traversed

blades having a different rated relative speed of rotation than the first-mentioned blades.

3. A steam turbine plant wherein steam is expanded from a substantially dry state to the wet state containing droplets of condensed moisture, comprising a casing, two shafts journaled in the casing for rotation in opposite directions, discs mounted on the shafts for rotation therewith, stationary discs fixed to said casing, alternating rings of blades mounted on said discs and disposed to be traversed by the steam while it is in the substantially dry state, and radially traversed rotating and stationary blades with entrance edges running in axial direction mounted on said rotating and stationary discs, respectively, and arranged to be traversed by the steam after it has been expanded to the wet state in the first-mentioned blades, said last-mentioned rotating and stationary blades having a lower rated relative speed than the first-mentioned blades, and an inlet for dry steam under pressure leading to the first mentioned rings of blades.

4. A steam turbine plant according to claim 3, wherein the two shafts have different rated speeds of rotation.

5. A steam turbine plant according to claim 3, wherein the rotating discs and the radially traversed blades cooperating with the stationary blades are distributed on both stub ends of one of said shafts, and means for distributing the wet steam to both ends of the shaft in parallel flow.

6. A steam turbine plant according to claim 3, wherein one part of the rotating blades adapted to be first traversed by the steam while it is in the substantially dry state is fixed to the same shaft as the rotating blades adapted to be traversed by the steam after it has been expanded to the wet state in the first mentioned blades.

7. A steam turbine plant wherein steam is expanded from a substantially dry state to the wet state containing droplets of condensed moisture, comprising a casing, two shafts rotating in opposite directions at different speeds and journaled in said casing, rotating discs carrying rings of blades and mounted on said shafts, the disc structure mounted on one of said shafts cooperating with part of the disc structure on the second shaft, and a stationary disc structure carrying rings of blades and fixed to said casing and cooperating with the remainder of the said rotating disc structure on the second shaft, the blades on the counterrunning discs being arranged to be traversed by the steam while it is in the substantially dry state, and an inlet for dry steam under pressure leading to said blades, the blades on the stationary disc structure and the rotating blades cooperating therewith being radially traversed with their entrance edges running in axial direction and being disposed to be traversed by the steam after it has been expanded to the wet state in the blading of said counterrunning discs.

8. A steam turbine plant wherein steam is expanded from a substantially dry state to the wet state containing droplets of condensed moisture, comprising a casing, two shafts journaled in the casing, blade carrying discs mounted on said shafts, an inlet for dry steam under pressure leading to said discs, radially traversed rotating blades with entrance edges running in axial direction adapted to be impinged by partially expanded wet steam and supported by said discs, radially traversed blades alternating and cooperating with the radially traversed rotating blades, said rotating blades being grouped into

blade rings providing channels in the path for the steam, said channels being so dimensioned and the number, diameters and normal speed of revolution of the rotating rings being so determined as to compel the steam to attain in the blades a velocity relative to said blades which is more than about 18% above the circumferential

speed of the aforementioned rotating blades relative to the blades cooperating with them, whereby the entrained drops of water are given a velocity of the order of said relative circumferential speed and erosion of the blades is reduced or 5 substantially eliminated.

ULRICH MEININGHAUS.
